BATTERY TERMINAL INSULATOR OR SIMILAR ARTICLE

Edward M. Wolf, Cranford, and Stanley J. Knoll, Keansburg, N.J., assignors to American Flange & Manufacturing Co. Inc., New York, N.Y., a corporation of Delaware

Continuation-in-part of design applications Ser. No. 1,590, Ser. No. 1,591, and Ser. No. 1,592, Mar. 22, 1966. This application Aug. 30, 1967, Ser. No. 8,436

Term of patent 14 years

Int. Cl. D13—02

U.S. Cl. D26—6

FIG. 1 is a top and side perspective view of a battery terminal insulator or similar article, showing one form of our new design wherein the insulator disc is surrounded by a metal sealing ring provided with a short inwardly extending tear tab;

FIG. 2 is a side elevational view of the form shown in FIG. 1;

FIG. 3 is a top plan view of the form shown in FIG. 1;

FIG. 4 is a cross-sectional view of the form shown in FIG. 1;

FIG. 5 is a top plan view of a battery terminal insulator or similar article showing a second form of our new design wherein the insulator disc is surrounded by a metal sealing ring provided with an elongated inwardly extending near tab which overlies the center portion of the insulator disc;

FIG. 6 is a side elevational view of the form shown in FIG. 5;

FIG. 7 is a cross-sectional view of the form shown in FIG. 5;

FIG. 8 is a top plan view of a battery terminal insulator or similar article showing a third form of our new design wherein the insulator disc is surrounded by a metal sealing ring provided with a diametrically extending tear tab having a central portion which overlies the center of the insulator disc;

FIG. 9 is a side elevational view of the form shown in FIG. 8; and

FIG. 10 is a cross-sectional view of the form shown in FIG. 8.

The essential features of the design and which are common to the several views shown comprise an insulator disc adapted to overlie the center terminal of a battery as shown in broken lines for illustrative purposes only. An annular metal sealing band surrounds the insulator disc and overlies the periphery of the same for securing the disc on a battery. The sealing band is provided with radially inwardly extending tear tab to facilitate removal of the band.

This is a continuation-in-part of design application Ser. No. 1,590 filed by Edward M. Wolf, Mar. 22, 1966, Ser. No. 1,591 filed by Stanley J. Koll, Mar. 22, 1966 and Ser. No. 1,592 filed by Edward M. Wolf, Mar. 22, 1966 all now abandoned.

We claim:

The ornamental design for a battery terminal insulator or similar article, substantially as shown and described.
